GARMENT HANGER

Robert J. King, Baltimore, Md.

Application June 13, 1957, Serial No. 665,389

1 Claim. (Cl. 223—88)

This invention relates generally to hanger devices, and more particularly to clothes hangers for use in supporting garments and the like.

One of the objects of this invention is to provide an improved garment hanger, having means thereon for preventing dresses, skirts and the like from slipping from the hanger.

Another object of this invention is to provide an improved garment hanger having detachable means thereon to facilitate the hanging of garments on the hanger and to eliminate soiling of clothes, by falling to the floor, particularly gowns and wraps.

Still another object of this invention is to provide an improved clothes hanger which has means thereon for centering various types of garments on the hanger in order to keep them in good condition.

And another object of the invention is to provide a hanger having adjustable and detachable supports thereon for variable disposition of the supports from the center of the hanger.

Still another object of the invention is to provide an improved hanger for use in supporting various types of garments which is economical to manufacture, efficient and reliable in operation, and which is easy to assemble and disassemble.

Other objects and many of the attendant advantages of this invention will be readily appreciated as the same become better understood by reference to the following detailed description, when considered in connection with the accompanying drawing, wherein:

Fig. 1 is a side elevation of a garment hanger illustrating supporting members in operative position thereon comprising this invention;

Fig. 2 is a perspective view of the embodiment of the invention illustrated in Fig. 1;

Fig. 3 is a side elevation of the embodiment of the invention of Figs. 1 and 2 in an extended position;

Fig. 4 is an enlarged bottom view of the embodiment of the invention of Figs. 1, 2 and 3;

Fig. 5 is a perspective view of a second embodiment of the invention;

Fig. 6 is an enlarged bottom view of the second embodiment of the invention of Fig. 5;

Fig. 7 is a perspective view of a third embodiment of the invention;

Fig. 8 is an enlarged bottom view of the third embodiment of the invention of Fig. 7;

Fig. 9 is a perspective view of a fourth embodiment of the invention; and

Fig. 10 is an enlarged bottom view of the fourth embodiment of the invention of Fig. 9.

Referring now to Figs. 1 to 4 of the single sheet of drawings, there is shown a clothes or garment hanger 12 having installed thereon a supporting member 10 at each end thereof, comprising this invention, for supporting garments or clothes of flimsy texture which would normally slip off of the hanger, such as dresses, skirts, slips, and the like. Each supporting member 10 consists of a

2

circular shaped body 14 having two ears 16 and 18 extending therefrom, as best seen in Fig. 3. As illustrated in Figs. 2 and 4, these ears 16 and 18 and the triangular shaped body 14 have overlapping portions 20. A starting crotch 22 is located at the upper ends of ears 16 and 18 to facilitate the positioning of the supporting member on the hanger 12. In actual operation, each supporting member is furnished in the form shown in Figs. 1, 2 and 4, after having been previously molded. Each supporting member is assembled to the coat hanger 12 by positioning the starting crotch 22 on the leg of the hanger 12 and pushing the two ear portions 16 and 18 apart and slipping them over the framework of the coat hanger. As shown in Fig. 1, the ears 16 and 18 prevent a garment having straps or the like thereon from slipping from the coat hanger 12.

As shown in Figs. 5 and 6, the supporting member 110 is of triangular shape in that it has a triangular shaped body portion 114, ears 116 and 118, and overlapped portions 120 and a starting crotch 122 corresponding to supporting member 10, tubular body 14, ears 16 and 18, the overlaps 20 and the starting crotch 22, respectively, described above in connection with Figs. 1 to 4. Otherwise, supporting members 10 and 110 are identical and function 25 in the same manner.

Instead of making the supporting member either circular or triangular, as shown in Figs. 1 to 6, the supporting member 210 can be formed of square cross-section as illustrated in Figs. 7 and 8. The supporting member 210 has a square body portion 214, ears 216 and 218, overlap portions 220 and a starting crotch 222, corresponding to the supporting member 10 of Figs. 1 to 4, including the circular shaped tubular body 14, the ears 16 and 18, the overlap portions 20, and the starting crotch 22, respectively.

The fourth embodiment of the supporting member 310 is shown in Figs. 9 and 10. This supporting member 310 consists of a semi-circular shaped body 314, a pair of 40 extending ears 316 and 318, overlap portions 320 and the starting crotch 322 corresponding to the supporting member 10, including the body portion 14, the ears 16 and 18, the overlap portions 20 and, the starting crotch 22 of Figs. 1 to 4.

It is to be noted that the supporting member 10, 110, or 310 can be formed of light metal, of rubber composition, plastic material, and/or other material such as heavy paper fiber and the like. It is to be noted that the supporting members 10, 110, 210, and 310 are easily installed and disassembled to the coat hanger 12, and are positioned as shown in Fig. 1 to prevent the garment from slipping from the hanger. The supporting members are durable and when one is damaged, it can be readily replaced without destroying the hanger.

Obviously many modifications and variations of the present invention are possible in the light of the above disclosure. It is, therefore, to be understood that within the scope of the appended claim the invention may be practiced otherwise than as specifically described.

What is claimed is:

As an article of manufacture, a supporting member for use with a garment hanger having a substantially triangular framework, comprising, structure defining a tubular body for encompassing said framework and having a slit therein extending in substantially the longitudinal direction throughout the length of said tubular body, said tubular body being formed so that the edges of said slit overlap and are substantially parallel to each other, and a pair of spaced, parallel overlapping ears extending in the longitudinal direction from one end of said tubular body

and arranged to define a starting crotch in alignment with said slit for use in assembling said supporting member to said framework of said hanger.
